UNITED STATES PATENT OFFICE.

GEORGE W. HOFMANN, OF CHICAGO, ILLINOIS.

HEAT-RESISTING RAIL.

1,262,794.

Specification of Letters Patent. Patented Apr. 16, 1918.

Application filed May 29, 1917. Serial No. 171,772.

To all whom it may concern:

Be it known that I, GEORGE W. HOFMANN, a citizen of the United States, residing at Chicago, in the county of Cook and State 5 of Illinois, have invented certain new and useful Improvements in Heat-Resisting Rails, of which the following is a specification.

The invention disclosed herein relates to 10 furnace rails arranged to support ingots, forgings, billets, or the like during their passage through a furnace. Two or more of the rails as herein described are to be used.

15 One of the objects of this invention is to provide a support for material to be conveyed through a furnace which will present a limited contacting surface and thereby reduce friction.

20 Another object of the invention is to provide a water-cooled rail which will obviate the difficulty due to "cold spots" on the metal conveyed, caused by water-cooled rails in common use.

25 Another object of the invention is to provide a heat-resisting rail in which the conveying bar will be held against warping or other distortion in shape so as always to present a level surface to the material to be 30 conveyed.

Another object of the invention is to provide a heat-resisting rail in which the conveying bar may be easily and quickly removed for replacement.

35 Another object of the invention is to provide a heat-resisting rail that may be readily inserted or replaced in any furnace of ordinary construction.

In the embodiment of my invention here- 40 in shown by the accompanying drawings, Figure 1 is a fragmental side elevation of my improved heat-resisting rail. Fig. 2 is a section thereof taken on the line 2—2 of Fig. 1.

45 Referring to the drawings, 3 and 4 are opposite flanges forming a supporting member. These flanges are preferably made of cast iron, and may be held together when in place by bolts 5. The heads 6 and nuts 7 50 of the bolts 5 are countersunk in the respective flanges 3 and 4. The flanges 3 and 4 are formed with circular openings at the top for the reception of a bar 8, and similar openings at the bottom for the reception of 55 a pipe 9. The upper openings are so arranged that the center of the bar which they

embrace will lie slightly below the upper surface of the flanges.

The bar 8 is a solid bar of refractory material, preferably wrought iron, and affords 60 the supporting surface for the travel of material through the furnace. It may be inserted in place by loosening the nuts 7 on the bolts 5. When these are again tightened, the bar 8 is firmly held in position and 65 cannot warp or twist under the heat of the furnace. When worn at the top, it may be rotated to present a new contacting surface, or may be removed and another bar substituted, by loosening the bolts 5. 70

The pipe 9 is adapted to be connected with a source of water supply and to be constantly supplied with a circulation of cold water. The heat from the materials being conveyed passes directly through the bar 75 8 and the flanges 3 and 4 and is absorbed by the water circulating in the pipe 9.

It will be seen that the pipe 9 extends below the lower surface of the flanges 3 and 4, thus adapting it to be partially embedded 80 in the floor of the furnace to hold the supporting flanges in position. It is preferably made with a diameter equal to the thickness of a standard brick, thus facilitating the installation or removal of the rail. 85

I claim as my invention:

1. A heat-resisting rail comprising an adjustable supporting member, a bar of refractory material supported and held against movement by said member, and a 90 water-cooled pipe embraced by said member.

2. A heat-resisting rail comprising a bar of refractory material, a water-cooled pipe longitudinally disposed with relation to said 95 bar, and a member formed of heat conducting material and embracing said bar and said pipe.

3. A heat-resisting rail comprising a bar of refractory material, a water-cooled pipe 100 extending longitudinally of said bar, and a heat-conducting member in contact with said bar and said pipe.

4. A heat-resisting rail comprising two oppositely disposed flanges, retaining bolts, 105 a round bar embraced by said flanges and adapted to form a support, and a water-cooled pipe embraced by said flanges.

5. In a heat-resisting rail, the combination of a bar of refractory material, a supporting member therefor formed of heat-conducting material, and a longitudinally 110

disposed water-cooled pipe in contact with said support.

6. In a heat-resisting rail, the combination of a bar of refractory material, a water-cooled pipe, and an adjustable supporting member adapted to support and hold in place said bar and to embrace said water-cooled pipe.

7. In a heat-resisting rail, the combination of a bar of refractory material, a supporting member made in two parts and hav-

ing at the top a circular aperture adapted to partially embrace said bar and hold it against lateral or vertical movement, means for adjustably connecting the two parts of said member, and a pipe in contact with said member and adapted to contain a cooling fluid.

In testimony whereof, I have hereunto set my hand.

GEORGE W. HOFMANN.
